E. C. KEMPER

CANOE TENT

Filed April 21, 1921

Fig. 2.

UNITED STATES PATENT OFFICE.

EDWARD C. KEMPER, OF WASHINGTON, DISTRICT OF COLUMBIA.

CANOE TENT.

Application filed April 21, 1921. Serial No. 463,331.

To all whom it may concern:

Be it known that I, EDWARD C. KEMPER, a citizen of the United States, and a resident of the District of Columbia, have invented 5
an Improvement in a Canoe Tent, of which the following description, in connection with the accompanying drawings, is a specification, like characters on the drawings representing like parts.

10 My invention relates particularly but not exclusively to the adaptation of a canoe, boat or like contrivance to form a tent or other shelter.

15 My invention will be best understood from the following description when read in light of the accompanying drawings of a specific embodiment of my invention submitted for illustrative purposes, while the scope of my invention will be particularly pointed out 20 in the appended claims.

In the drawings:

Fig. 1 shows in elevation a canoe with its support and the shelter assembled;

25 Fig. 2 is an end elevation according to Fig. 1;

Fig. 3 is a plan of the supporting frame-work;

Fig. 4 is an end elevation according to Fig. 3;

30 Fig. 5 is a detail of the frame-work;

Fig. 6 is a detail of the lower end of the supporting legs; and

35 Figs. 7 and 8 are respectively sections on the lines 7—7 and 8—8 of Fig. 1, with parts omitted.

40 In the submitted embodiment of my invention, which I have selected for illustrative purposes, I support the canoe 1 on a compatible frame-work which comprises the end pieces 2 and 3 and the side members indicated in their entirety at 5 and 7. I have shown the end members formed of a rod bent to form the end eyes 9 and at an intermediate portion thereof an eye 11.

45 Carried by the end members and in articulate relation thereto are legs 13 having at their upper ends eyes 15 for engaging the eyes 9 and the leg 17 having a similar eye 19 engaging the eye 11. The ends of the rod are continued past the end eyes 9 to form terminal pieces 21 set at an angle to the body of the rod.

The side members I prefer to make com-

pactible and for this purpose I provide the ends of the terminal pieces 21 with coupling sleeves 23 permanently secured thereto in order to provide a screw-threaded socket into which the screw-threaded ends of the sections 25 of the side members may be detachably threaded. The opposite end of one 60 of the sections 25 of each side member is provided with a coupling sleeve 27 in engagement with the screw-threaded portion 29 of the section, which sleeve may be turned to cause it to project over the end of the 65 section to engage the screw-threaded portion 31 of the end of the adjacent section 25 to hold the sections in assembled relation.

The ends of the legs 13 and 17 rest on the ground and for this purpose are preferably 70 provided with points 33 to permit the same to be easily forced into the ground, and for gaging the depth of insertion and for preventing the legs from being forced farther into the ground than desired each leg is 75 provided adjacent its end with a shoulder portion consisting of a plate 35 formed with a flange 37 secured to the leg by a pin 39. The flange 37 is set at an angle to the plate in order that the bottom surface of the plate 80 may conform to the normal level of the ground.

In erecting the frame-work, one of the end pieces may first be set up with the legs 13 extended transversely to the length of 85 the canoe and the leg 17 extended longitudinally the length of the canoe as illustrated by Figs. 3 and 4. After erecting this end piece, the adjacent sections 25 of the side members 5 and 7 may be attached thereto, 90 and after attaching the remaining sections to the other end piece the sleeve 27 may be caused to couple the sections together, and the legs of the other end member may then be forced into the ground in the same manner as those of the end member heretofore erected.

The canoe may be of any suitable or usual design. The standard canoe, the hull of which is of a shape substantially that illustrated by the drawings is provided with gunwales 43 and thwarts in the form of seats located adjacent opposite ends of the canoe and transverse braces 45, the thwarts being suspended from beneath the gunwales 100 as indicated by Figs. 7 and 8.

After the frame is erected, the canoe is placed in inverted position upon the framework in such manner that all or some of the thwarts—the number depending on the length of the frame—rest on the side members 5 and 7. Although I may form the side members to conform with the gunwales of the canoe I prefer, in order to adapt the frame-work to different sizes of canoes, to make the frame with the side members spaced a distance less than the beam of the canoe at the mid-ship section and after placing the canoe on the framework to spread the side members to make them approximately conform with the contour of the gunwales. For this purpose in the submitted embodiment of my invention I provide the C-clamps 47, which I have shown slidably attached to the sections 25 by means of eyes 49 formed integrally with the jaws of the clamps. These clamps, which may be of any usual or suitable construction are each provided with a head 51 receiving the screw 53 and the latter provided with the head 55 attached to the screw by a universal joint in a known manner.

For causing the frame-work to be easily spread I preferably construct the framework of rods small enough to be resilient and for added flexibility make the eyes 9 and 11 of larger diameter than the material of the legs engaging said eyes. In clamping the side members to the gunwales the screws of the clamp will be first screwed out to provide the maximum space between the head 55 of the screw and the jaw of the clamp, after which the side members will be forced outwardly to hook the head 55 over the side of the canoe adjacent the gunwales. Further spreading of the side members can now be accomplished by operating the screw to close the clamp.

For providing side walls for closing the space between the gunwales and the ground I provide a single strip 57 of canvas or like material provided with a series of spaced open hooks 59 at its upper edge for engaging the side and end members of the frame in such manner as to support the upper edge of the canvas inside the hull of the canoe and adjacent the gunwales. The lower end of the canvas I provide with straps or like members 61 which are perforated to receive the pegs 63 adapted to be forced into the ground to secure the lower edge of the canvas. The adjacent ends of the strip are respectively provided with suitable engaging fastening means and as shown these are indicated by the row of clips 63 carried at one end of the strip and having perforations for engaging the buttons 65 carried at the other end of the strip. In the drawings I have shown for con-

venience of illustration the clips and buttons on the exterior surface of the strip. It will be understood however that in practice these devices may, if desired, be placed on the interior surfaces.

It will be observed that my support is compactible and that after the sections of the side members are detached from each other and from the end pieces, the legs may be folded against the body of the end pieces and all parts then wrapped in the canvas strip constituting the side walls to form a compact bundle.

Although I have described one specific embodiment of my invention for illustrative purposes, it is to be understood that I am not limited thereby to its particular mechanical details and that wide deviations may be made therefrom without departing from the spirit of my invention.

Claims—

1. A supporting means for a canoe for holding said canoe in inverted position entirely clear of the ground, said supporting means comprising legs and a compactible substantially rectangular frame supported by said legs, the side members of said frame being so spaced as to permit the thwarts of said canoe to rest thereon adjacent the gunwales of said canoe, and side walls of a shelter supported by said frame.

2. A supporting means for a canoe for holding said canoe in inverted position entirely clear of the ground, said supporting means comprising legs and a compactible substantially rectangular frame supported by said legs, the side members of said frame being so spaced as to permit the thwarts of said canoe to rest thereon adjacent the gunwales of said canoe, means for forcing said frame to conform to said gunwales, and side walls of a shelter supported by said frame.

3. A supporting means for a canoe for holding said canoe in inverted position entirely clear of the ground, said supporting means having legs and side members supported by said legs, said side members being disposed to lie between the gunwales of said canoe in spaced relation to each other and adjacent said gunwales to permit the thwarts of said canoe to rest thereon, and side walls of a shelter supported by said supporting means.

4. A supporting means for a canoe for holding said canoe in inverted position entirely clear of the ground, said supporting means having legs and side members supported by said legs, said side members being disposed to lie between the gunwales of said canoe in spaced relation to each other and adjacent said gunwales to permit the thwarts of said canoe to rest thereon, means for forcing said side members to conform to

- said gunwales, and side walls of a shelter supported by said supporting means.
5. A supporting means for a canoe for holding said canoe in inverted position entirely clear of the ground, said supporting means having legs and side members supported by said legs, said side members being disposed to lie between the gunwales of said canoe in spaced relation to each other
- 10 and adjacent said gunwales to permit the thwarts of said canoe to rest thereon, and the side walls of a shelter supported by said side members.
6. A supporting means for a canoe for holding said canoe in inverted position entirely clear of the ground, said supporting means having legs and side members supported by said legs, said side members being disposed to lie between the gunwales of said canoe in spaced relation to each other and adjacent said gunwales to permit the thwarts of said canoe to rest thereon, and means for attaching said side members to said canoe.
- 25 7. A supporting means for holding a canoe in inverted position, said supporting means having legs at each end of said canoe and compactible means for holding said legs in spaced relation.
- 30 8. A supporting means for holding a canoe in inverted position, said supporting means having legs at each end of said canoe, end members to which said legs are articulated in spaced relation to each other, and means for holding said end members in spaced relation.
- 35 9. A portable support for a canoe including compactible end members having a plurality of spaced legs, compactible means for holding said end members in spaced relation, and means carried by said support for attaching said support to said canoe.
- 40 10. In a support for a canoe or the like, separate end members comprising parts adapted to rest on the ground, means attached to said end members for holding said end members in spaced relation, and means for securing said canoe to said support having relatively movable parts for releasably engaging said canoe.
- 45 11. In a support for a canoe or the like, separate compactible end members comprising parts adapted to rest on the ground, means attached to said end members for holding said end members in spaced relation, and means for securing said canoe to said support having relatively movable parts for releasably engaging said canoe.
- 50 12. In a support for a canoe or the like, separate compactible end members comprising parts adapted to rest on the ground, a compactible means adapted to be attached to said end members for holding said end members in spaced relation, and means for se-
- curing said canoe to said support having relatively movable parts for releasably engaging said canoe.
- 55 13. A supporting means for a canoe having gunwales and thwarts, said supporting means having side members on which said thwarts are adapted to rest, means for securing said side members to said gunwales, and a curtain adapted to form a side wall.
- 60 14. A support for a canoe comprising a resilient frame having side members spaced at a distance less than the maximum distance between the gunwales of said canoe, and means for spreading said side members to cause them to approach said gunwales.
- 65 15. A support for a canoe comprising a resilient frame having side members spaced at a distance less than the maximum distance between the gunwales of said canoe, and means for spreading said side members to cause them to approach said gunwales and for securing said members thereto.
- 70 16. A support for a canoe comprising separate end members, members for attachment to said end members and extending from one to the other, a curtain, and means for attaching said curtain and said canoe to the second named members.
- 75 17. A supporting means for a canoe having gunwales, said supporting means having end members adapted to rest on the ground, side members extending from one end member to the other, and means for securing said side members to said gunwales.
- 80 18. A support for a canoe comprising a substantially rectangular frame, and means for causing the sides of said frame to substantially conform to the contour of the gunwales of said canoe.
- 85 19. A support for a canoe comprising end pieces having means adapted to rest on the ground, and means for securing said end pieces to said canoe.
- 90 20. A support for a canoe comprising end pieces having means adapted to rest on the ground, and means for securing said end pieces to the gunwales of said canoe.
- 95 21. A support for a canoe comprising end pieces, legs articulated to said pieces, means providing for the securing of said legs to the ground, side members extending from one end piece to the other and detachable therefrom, said side members being spaced from each other a distance less than the space between the gunwales of said canoe, means for securing said members to said gunwales, and a curtain having means for attachment to said side members.
- 100 22. The combination with a support for a canoe, said support having legs and side members, said side members extending lon-

itudinally of the canoe in proximity of the gunwales thereof, of a curtain forming a side wall and suspended from one of said members.

5 23. The combination with a support for a canoe, said support having legs and side members, said side members extending lon-

itudinally of the canoe within the hull and in proximity of the gunwales thereof, of a curtain forming a side wall and suspended from one of said members. 10

In testimony whereof, I have signed my name to this specification.

E. C. KEMPER.
